AIR VENT VALVE

Lewis W. Eggleston, Davison, Mich., assignor to
 Detroit Lubricator Company, Detroit, Mich., a
 corporation of Michigan

Application April 22, 1940, Serial No. 331,005

17 Claims.

(Cl. 236—61)

My invention relates generally to valves and more particularly to air vent valves for heating systems.

One of the objects of my invention is to provide a new and improved air vent valve of the type adapted to vary the rate of egress of air from a heating system in accordance with the pressure in the system to determine the rate of admission of a heating medium to a heat transfer element of the system.

Another object of my invention is to provide an air vent valve in which the noise formerly caused by air escaping to atmosphere is eliminated.

Another object of my invention is to provide an air vent valve having provisions for removing entrained moisture from the air prior to egress of the air from the valve.

Another object of my invention is to provide an air vent valve of the above mentioned character having a new and improved arrangement of the operating and associated parts thereof.

Another object of my invention is to provide an air vent valve having provisions of a simple and inexpensive character to vary the rate of egress of air by the valve in accordance with the pressure in a heating system.

Another object of my invention is to provide an air vent valve having new and improved mechanism for regulating or adjusting the venting capacity of the valve.

The invention consists in the improved construction and combination of parts, to be more fully described hereinafter and the novelty of which will be particularly pointed out and distinctly claimed.

In the accompanying drawing, to be taken as a part of this specification, I have fully and clearly illustrated my invention, in which drawing—

Figure 1 is a top plan view of my improved air vent valve;

Fig. 2 is a vertical central sectional view of my valve taken along the line and in the direction of the arrows 2—2 of Fig. 1;

Fig. 3 is a view of my device shown in cross-section, taken along the line and in the direction of the arrows 3—3 of Fig. 2;

Fig. 4 is a fragmentary view shown in section of my device, taken along the line and in the direction of the arrows 4—4 of Fig. 3;

Fig. 5 is a fragmentary view of my device shown in cross-section, taken along the line and in the direction of the arrows 5—5 of Fig. 4;

Fig. 6 is a fragmentary view of my device shown in cross-section, taken along the line and in the direction of the arrows 6—6 of Fig. 2;

Fig. 7 is an enlarged detail view of certain of the valve members shown in the transitory position of their simultaneous engagement with their concentrically arranged valve seat portions;

Fig. 8 is a view shown in perspective of a valve member of my air vent valve, and

Fig. 9 is a view of a modified valve member for my air vent valve.

- 5 Referring to the drawing by characters of reference my air vent valve includes a casing 1, preferably of general tubular form having a top wall 2, a continuous side wall 3 and a bottom wall 4. The side wall 3 has an annular offset surface 4^a formed by the telescopic union of upper and lower side wall portions and having a function to be described. The casing 1 has a nipple 5 in the form of an open ended tubular fitting that may be secured in and to the 10 casing side wall 3 adjacent the casing bottom wall 4. An outer end portion of the nipple 5 may be threaded, as at 6, for screw-threaded connection to a steam radiator or heat transfer element of a heating system (not shown). Extending longitudinally through the nipple 5 there is shown a siphon tube 7 for the return to the radiator of any water that may happen to find its way into the valve casing 1. An aperture 8 is preferably provided through the side wall of the nipple 5 15 for the passage of air from the radiator into the valve casing 1, the aperture 8 preferably opening upward into the casing, as shown.

- Mounted on and rigidly secured to the casing top wall 2 there is a valve seat member or body 30 10 that projects into the casing through, and closes an opening in, the casing top wall 2. Preferably the valve seat member 10 has a plate-like portion 11 that may seat on the upper surface of the casing top wall 2 and has a passageway 12, which is preferably a hollow cylinder having a downwardly directed open end within the casing 1. The cylinder 12 preferably has its longitudinal axis extending substantially vertically and this hollow cylinder may be defined by a tubular extension or portion 13 which may be integral with, and depend from, the plate-like portion of the valve seat member 10. The cylinder or passageway 12 opens upwardly into a relatively small passageway 14 provided in the valve 35 seat member 10, the passageway 14 preferably being a vertically extending bore disposed in longitudinal axial alignment with the cylinder 12. The passageway or bore 14 opens through the upper surface of the plate-like portion 11 and at lower end there is a downwardly facing port and seat 16 for cooperation with a valve member 17. The cylinder 12 and bore 14 provide a passageway through the valve seat member 10 for the escape or egress of air from the casing 1. The internal diameter of the cylinder passageway 12 is larger than the diameter of the bore or passageway 14 and terminates in an upper end wall forming a shoulder which is preferably conical, as at 18, the shoulder providing a valve seat 50 which tapers or converges inwardly preferably to

the port 16 of passageway 14. The valve member 17 extends upwardly, longitudinally within the cylinder 12, and the upper end or face of the valve is preferably rounded, as at 29.

The valve member 17 is preferably carried by and rigidly secured to the top of a thermostatic float, designated in general by the numeral 21, which is disposed within casing 1 below the valve seat member 18. The thermostatic float 21, as shown, is a well known type having a closed container 22 charged with a temperature responsive, expansible-contractible fluid such as, for example, alcohol. Below the lower end of the thermostatic float 21 there is a supporting member 23 therefor, preferably a screw that is vertically, adjustably screw-threaded into a substantially horizontally extending metallic strip 24 that may have its opposite ends secured in and to the casing side wall 3. The screw 23 is arranged so that the bottom wall, as at 25, of the thermostatic float 21 seats centrally thereof on the upper end of the screw. The bottom wall 25 of the container 22 is flexible and flexes downwardly on expansion of the fluid in the container. This causes the container 22 to move upward carrying with it the valve member 17 which moves toward and is adapted to engage its seat 16 to prevent escape of the heating medium through the air vent passageway 14.

A pressure responsive, piston type valve 27 is provided to control flow of air through the passageway 14 and is arranged for vertical movement within and longitudinally of the cylinder 12. The valve member 27 is preferably of general tubular form having its opposite ends open, and surrounds and cooperates with the thermostatic float valve 17 and the conical seating surface 18 to control flow through the passageway 14. The valve member 27 loosely surrounds the valve member 17 so as to be freely movable relative thereto and so as to provide an annular passageway 28 therebetween for restricted flow or passage of air. The upper end of the valve member 27 is preferably rounded, as at 29, entirely therearound providing a seating surface or face for seating against the conical wall 18 of the cylinder 12. The valve member 27 has a piston portion 30 which may be an outturned, external annular flange, preferably provided at the lower end of the valve member. The piston portion may be cylindrical in shape and the diameter thereof is slightly less than the diameter of the cylinder 12 so as to provide an annular space 31 between the piston side wall and the wall of the cylinder for restricted flow or passage of air. The valve member 27 is carried by the valve member 17 which is formed having an upwardly facing, external shoulder or seating surface 32 on which the valve 27 is adapted to seat, as shown in full lines Fig. 2. Preferably the valve member 27 is arranged such that when it is seated on the shoulder 32 and the valve 17 is open, the piston portion 30 of the valve member extends slightly within the cylinder 12. As will be apparent from the foregoing and from the showing of Fig. 7, the portion 32^a of surface 18 closely surrounding port 16 serves as a seat for valve member 17, and an annular portion 32^b of surface 18, spaced from surface portion 32^a, serves as a seat for valve member 27. As is pointed out hereinafter, the valve member 27 is engageable with the outermost seat portion 32^b upon occurrence of a pressure differential, and the valve member 17 is engageable with the innermost seat portion 32^a under the

action of thermostatic float 21, however, it should be noted that when valve member 27 is seated as shown in Fig. 7 that upon the valve member 17 closing the port 16, as is also shown in Fig. 7, the pressure above and below valve member 27 will be equalized so that the valve member 27 will thereupon fall to its seat on shoulder 32 of the valve stem.

A plate-like, manually operable valve 33 is provided and seats on the top surface of the valve seat member 10, the valve 33 being operable to regulate the venting capacity of the air vent valve. The manually operable valve 33 is preferably pivoted on an upstanding pivot pin 34 that may have one end secured in and to the valve seat member 10. The valve 33 overlies the discharge opening of the passageway or bore 14 and in its underside has a recess or outlet chamber 35 providing a passageway having an opening, as at 36, through the side of the valve for the egress of air. The recess or chamber 35 in the manually operable valve 33 is preferably of larger capacity or sectional area, in a plane normal to the direction of air flow than the passageway 14 so that air, on entering chamber 35 from the smaller passageway 14, will be permitted limited expansion thereby decreasing its velocity. The passageway 35 diverges toward its outlet 36, increasing in cross-sectional area normal to the direction of air flow so as to provide for expansion of the discharging air. The passageway 35 also has a curved wall portion 35^a for changing the direction of air flow so that the member 33 may be made compact and the air be properly directed. As is more clearly shown in Fig. 3, the manual adjustment valve 33 is shown in a position such that substantially only one half the area of the discharge opening of the air outlet passageway 14 is uncovered or in communication with the passageway 35 of the valve 33, the other half of the area of the discharge opening of the air outlet passageway 14 is uncovered or in communication with the passageway 35 of the valve 33, the other half of the area of the discharge opening 14 being covered or closed off by the valve. In this position of the valve 33 it will readily be seen that the device is set to vent at one half of the rate of its venting capacity. If the valve 33 is pivoted in a clockwise direction, as seen in Fig. 3, more of the area of the discharge opening of passageway 14 will be uncovered or will communicate with the passageway 36 through the valve 33, with corresponding increase in the rate of venting of air by the device. Conversely, if the valve 33 is rotated in a counterclockwise direction the area of the discharge opening of passageway 14 communicating with the passageway 36 of the valve will be decreased with corresponding decrease in the venting capacity of the device. A leaf spring or strip of metal 37, and a screw 38 for holding the spring under tension, may be provided to lock or hold the valve member 33 against movement from a desired position of adjustment. The opposite ends of the leaf spring 37 may be bifurcated and one end may be positioned under the head of pin 34 and the other end may be positioned under the head of the screw 38. The screw 38 may screw-thread into the upper end of the valve seat member 10 and is preferably disposed so that its head overlaps the plate-like valve member 33. The leaf spring 37 is preferably formed or bent so that when the screw 38 is tightened down the spring will be placed under tension

and will be drawn down against the upper surface of the valve member 33.

Preferably the casing 1, valve seat member 10 and adjustment valve 33 are enclosed by a casing 40 which may be of general tubular form, the casing 40 preferably being constructed of a heat insulating material. The casing 40 is preferably provided with a slot or aperture 41 through its top wall, and the manually operable valve 33 is preferably provided with an operating arm 42 which may project externally of the casing 40 through the slot 41. In the present instance, the operating arm 42 at its outer end, externally of the casing 40, has an upturned portion or handle 43. The outer casing 40 may be held in place by a single screw 45 that may extend into the casing through the side wall thereof and have an inner and preferably pointed end 46 for engaging in a recess in the side wall of the valve seat member 10, externally of the inner casing 1. Through the top wall of the outer casing 40 there is provided an aperture 44 through which access may be had from externally of the casing to the screw 38, with a tool such as a screw driver. The inner top wall surface of the outer casing 40 is spaced from and above the valve seat member 10 and cooperates therewith to provide a chamber 47 into which air discharges from the passageway 35 of the valve member 33. The chamber 47 is of larger capacity or sectional area, in a plane normal to the direction of flow of air, than the valve chamber or passage 35 so that on egress of air from the valve chamber outlet 36, the air will expand in the larger chamber or space 47 with a consequent decrease in velocity. The inner wall surface of the outer casing 40 is spaced from the outer wall surface of the inner casing 1, and preferably has a plurality of spaced, vertically extending ribs 48 and 48^a. Between the inner and outer casings, on opposite sides of the rib 48^a, there are vertically extending passageways 50 that communicate with the chamber or space 47 above the valve seat member 10. Preferably the passageways 50, taken together, have a larger capacity than the chamber 47 so that air, on entering the passageways from the chamber 47, will further expand. The ribs 48 and 48^a preferably terminate at their lower ends intermediate the top and bottom of the casing 40 and below their terminal ends there is an annular chamber or space 52 between the side wall of the inner casing 1 and the outer casing 40. The top wall of chamber 52 is formed by the annular flange 6^a of the casing 1. This chamber 52 receives the air and vapor discharging from passageway 35 through the channels or passageways 50. Opening through its side wall the outer casing 40 is provided with an aperture or slot 53 to receive the nipple 5, the slot 53 preferably running out of the lower open end of the casing 40. The slot 53 also provides an opening from the casing 40 for the escape of air therefrom to outside atmosphere, and the area of this opening is made sufficiently large so that there will be little or no danger of its being painted closed in the event that the outer casing should be painted to match the radiator. The lower end of the outer casing 40 may be closed by a plate-like, removable closure member 54. The closure member 54 may be held in place by a U-shaped member having a base 55 secured to the closure member and having upstanding, resilient portions 56 adapted to position between and engage the spaced walls of the inner casing 1 and the outer casing 70

40. As seen in Fig. 6, when the closure member 54 is pushed into place the resilient portions 56 are forced inwardly toward each other and bowed and placed under tension to thereby frictionally hold the closure member to the outer casing 40. Also, the resilient holding means acts to hold the inner and outer casings together and in proper positions relative to each other.

The operation of my air vent valve is as follows: Valves of the character herein described are particularly suited for heating systems having a single supply line with a common return line, because the venting capacities of the valves may be adjusted in such a manner as to obtain substantially equal and quick distribution of the heating medium to all of the radiators in the line. For example, by means of the adjustment valve 33 the first valve in the line may be set so that only a small portion of the area of its venting port is open, and succeeding valves may be set to have successively larger venting capacities. As the steam or other heating medium proceeds through the system to the radiators, it pushes ahead of it the air in the system, causing an increase in pressure therein. When the valves are set or adjusted so that their venting capacities vary, increasing in capacity from the first to the last valve in the line, the resistance of the air to the entrance of steam in succeeding radiators decreases from the first to the last radiator, which induces steam to flow quickly to all of the radiators. The air flows through the casing 1 and passes therefrom through the cylinder 12 and passageway 14. From the passageway 14 the air flows into the passageway or chamber 35 in the adjustment valve 33, where it expands and whence it takes an abrupt turn and discharges through valve chamber opening or outlet 36 into the chamber or space 47 between the spaced top walls of the inner casing 1 and the outer casing 40. The outlet 36 directs the air away from the apertures 41 and 44 and directly toward the spaces 50. From the chamber or space 47 the air further expands and flows down through the spaces or passageways 50 to the bottom of the outer casing 40 where the air escapes to outside atmosphere through the opening or slot 53. It will be noted that the head of screw 38 substantially closes the opening 44 and that the air discharging from valve chamber outlet 36 must be completely reversed in flow direction for escape through the partially blocked adjustment opening 41 (see Figs. 2 and 3) so that the air which is discharged as shown by the arrows in Fig. 5 will be required to turn through only a right angle for its more free downward discharge. By providing for the air to escape into the enclosed chamber 35 of the valve 33, and by providing for stepped or gradual expansion of the air, as set forth above the hissing noise which formerly occurred in valves of this character is prevented or is inaudible. The outer casing 40 provides a secondary expansion chamber for the air to deaden the sound of the escaping air. The pressure responsive piston valve 27 remains on its seat 32, or in its down position, so long as the pressure in casing 1 does not exceed a predetermined pressure. If the pressure in the casing 1 should increase to a predetermined pressure, then the valve 27 will be moved upward thereby into engagement with its seat portion 32^b. When the valve member 27 is seated, it will be seen that the only path of escape for the air will be via the small annular passageway 28 between the inner wall surface

of the valve 27 and the outer wall surface of the thermostatic float valve 17. This will further restrict egress of air from the casing 1 with the result that the accompanying increased air pressure in the casing and radiator will, with greater effect, oppose entrance of the heating medium into the radiator. Thus the pressure responsive valve 27 acts to provide for substantially equal and quick distribution of a heating medium throughout a heating system. On predetermined decrease in pressure in the system, the valve member 27 descends by gravity to its seat on shoulder 32 thereby increasing the venting capacity of the valve. When steam or water enter the casing 1, the thermostatic float 21 is respectively heated or buoyed up thereby and moves valve 17 upward against its seat portion 32a to close the passageway 14 to flow of the heating medium therethrough and if valve member 27 is in flow reducing position upon closure of valve 17, then equalization of pressure as above described causes the valve member 27 to open and fall to its seat on shoulder 32. The heat insulating outer casing 40 also prevents rapid dissipation of the heat imparted to the inner metallic casing 1 by the heating medium, so that if any moisture such as that entrained in the vented air gets into the chamber 52 between the two casings it will be evaporated. The water vapor on discharge from the outer casing 40 will be taken up by the outside atmosphere and thus dripping of water on the floor is prevented.

In Fig. 9 there is shown a modified form of the valve member 27 and of the cylinder 12 in which modification the upper end wall of casing 1 and in particular the seat member 10 has a downwardly extending hollow cylindrical portion 57 generally similar to the tubular extension 13 of Fig. 2 and providing an inlet passageway 57a of larger diameter than and leading to the port or passageway 14 as in Fig. 2. The inside diameter of portion 57 is greater than the outside diameter of the valve member 17 and has at its lower end portion a seating surface 58. The upper end portion of valve member 17 extends into the passageway 57a and serves as a guide for a plate-like disk valve member 59 having a central aperture therethrough which loosely receives a reduced diameter portion 60 of the valve member 17. The valve member 59 is adapted in one of its positions to seat on the valve stem shoulder or seating surface 32 formed at the intersection of the normal diameter portion of the member 17 with the portion 60 and to have this position irrespective of whether the valve member 17 is closed or open, and in another position to seat against the seating surface 58 when valve member 17 is open. When the velocity of air flow through the passageway 14 of Fig. 8 exceeds a predetermined value, then the disk member 59 which is sufficiently thin to be light in weight is lifted into its position against the surface 58, as shown in dotted lines, to limit or restrict flow through the passageway 14 so that the aperture through the disk member 59, which is sufficiently larger than the portion 60, forms an annular flow passageway 61 similar to passageway 28 of Figs. 2 and 7. The spacing of shoulder 32 from shoulder or wall 18 permits the valve member 17 to move to closed position when the disk member 59 is seated and also allows disk member 59 to move to open position when valve member 17 is seated. It will be noted that the shoulder or end wall 18 and the annular end portion 58 of the casing upper end wall provide

valve seat portions concentric with passageway 14 and spaced from each other for engagement respectively by the valve member 17 and the valve disk or member 59, the valve member 17 engaging the innermost annular seat portion 18 and the valve member 59 engaging the outermost annular seat portion 58.

From the foregoing description it will now be seen that I have provided a new and improved air vent valve having a pressure responsive valve member which operates "on" and "off" in accordance with pressure in the system to vary the air venting capacity of the valve whereby to control supply or delivery of a heating medium in the system to the heat exchangers or radiators. I have also provided an air vent valve which will vent air without the usual hissing noise common in such devices. Furthermore, I have provided an air vent valve of a character such that the water entrained by the air is vaporized prior to its escape to outside atmosphere. In addition I have provided an air vent valve having new and improved adjustment means to regulate the venting capacity of the valve.

This application is a continuation in part of my copending application S. No. 159,554, filed August 17, 1937, for Air vent valves.

What I claim and desire to secure by Letters Patent of the United States is:

1. In an air vent valve for a heating system, a casing having a passage through a wall thereof including a valve seat member, a thermostatic valve in said casing and extending into said passage, said valve cooperating with said passage to provide an annular chamber therebetween and being operable to engage said seat member to close said passage to flow therethrough, said valve having a seat spaced from and opposed to said seat member, a pressure responsive open ended tubular valve surrounding said first-named valve and arranged to move longitudinally thereof within said annular chamber and carried by said first-named valve on said seat, said second-named valve being movable relative to said first-named valve longitudinally of and within said annular chamber, said second-named valve on increase in pressure in said casing engaging said seat member and cooperating with said first-named valve to increase the resistance to flow through said passage.

2. In a vent valve, a casing having a valve port with an outlet passageway leading thereto, said casing having a seat within said passageway and surrounding said port, a first valve member longitudinally movable in said passageway and controlling said port, a second valve member positioned in said passageway and engageable with said seat to control said port, said second valve member being movable relative to said first valve member and having an area obstructing flow through said passageway such that said second valve member will be moved to said seat by a difference of fluid pressure between the pressure within said casing and the pressure on the outlet side of said port.

3. In a vent valve, a casing having a valve port with a passageway leading thereto, said casing having a seat within said passageway and surrounding said port, a first valve member within and vertically reciprocal in said passageway, an apertured valve member within said passageway and surrounding and guided on said first valve member, said apertured valve member being lifted to said seat by difference of fluid pressure between the pressure within said casing and the

pressure on the outlet side of said port, and means operable to reduce flow through said port upon engagement of said apertured valve member with said seat, said first valve member being movable through the aperture of and relative to said apertured valve member to close said port.

4. In a vent valve, a casing having an opening through its top wall, a plate member closing said opening, said member having a valve port and having a cylindrical outlet passageway of enlarged cross-section leading to said port, said plate member having an annular seat portion interposed between the wall of said passageway and the wall of said port, an automatic valve member reciprocal in said passageway and operable to close said port, a pressure responsive valve member within said passageway and surrounding said automatic valve member and spaced from the wall of said passageway to determine the venting capacity of said port when said valve members are open, said pressure responsive valve member moving to said seat portion upon a differential of fluid pressure between the pressure within said casing and the pressure on the outlet side of said port, means operable upon engagement of said pressure responsive valve member with said seat portion to reduce the rate of flow of fluid through said port, a valve plate overlying said port and pivotally supported on and for sliding engagement with the top face of said plate member, and means urging said valve plate into engagement with said plate member, said valve plate being operable to require an increased pressure in said casing for movement of said responsive valve member to said seat portion.

5. In a vent valve a casing having a top wall with a flat outer top surface and containing a chamber with an outlet port opening upwardly through said wall surface, an automatic valve in said chamber and operable to control flow through said port, a valve plate seating on said wall surface and overlying said port and having a flat surface portion engaging said wall surface, said valve plate having a recess in its surface portion with an edge portion movable across said port to control discharge from said chamber, said recess having an upper wall movable into overlying relation to said port and against which the fluid discharging through said port impinges, said valve plate having an opening through its side wall for discharge of fluid from said recess so that fluid admitted to said recess from said port is discharged at substantially a right angle relative to direction of inflow of fluid to said recess, means pivotally supporting said valve plate on said top wall, and resilient means acting on said valve plate to hold said surface portion tightly against said top wall surface.

6. In a vent valve, a casing having a flat external top wall portion and having an outlet port leading through said portion, a housing member overlying and surrounding said casing and having a plurality of apertures through its top wall, an automatic valve in said casing controlling flow through said port, a valve plate within said housing member and overlying said port and slidably seated on said portion and having a portion extending through one of said apertures, means pivotally securing said plate to said casing for swinging movement across said port to control flow therethrough, resilient means within said housing member holding said valve

plate tightly against said wall portion to prevent leakage between said wall portion and said plate and to frictionally oppose movement thereof, said valve plate acting to maintain substantially constant the restriction to fluid flow from said outlet at a desired value, and means for adjusting the holding effect of said resilient means and positioned adjacent another of said apertures for operation externally of said housing member, said adjusting means being operable to lock said valve plate against movement by said extending portion.

7. In an air vent valve, a casing having an outlet port with a seating surface, an adjustable valve member cooperable with said surface to form a valve means for controlling flow through said port, and means providing an elongated air flow passageway leading from the outlet side of said valve means and operable to conduct air from said valve means, said passageway having an outlet of larger flow area than said valve means and having a streamline contour of progressively increasing cross-sectional flow area to its outlet so that the air discharging through said valve means will have a progressively gradually decreasing velocity prior to discharge from said passageway thereby to reduce the noise of air discharging from said valve means.

8. In a vent valve, a casing having a chamber with an outlet port at its upper end portion, an automatic valve in said chamber and controlling said port, a housing overlying and surrounding said casing and having an upper end wall spaced from said casing, said housing having an opening through said end wall, a manually operable valve pivotally mounted to swing across said port to control flow through said port and operable to maintain a desired substantially constant restriction to fluid flow, a clamping spring operable to hold said manually operable valve in adjusted position, means to adjust the tension of said spring and operable to prevent movement of said manually operable valve, said housing having an aperture therethrough for access to said adjusting means, and an operating member rigid with said manually operable valve and positioned between said casing and said end wall and having a finger grip portion projecting through said end wall opening.

9. In a vent valve for a steam system, a casing having a chamber for communication with the system and to be heated by steam admitted from the system, said chamber having an outlet port at its upper end portion, an automatic valve in said chamber and controlling said port to allow air to flow through said port thereby to vent the system, a housing overlying and surrounding said casing and having an imperforate side wall and having an outlet at its lower end portion and having an opening through its upper end portion, said housing and said casing cooperating to form an annular passageway, an adjustable valve member carried by said casing and determining the effective flow area of said port and adjustable from externally of said housing through said upper opening, and means to direct air-entrained liquid discharging from said port into said annular passageway so that the discharging liquid will pass over and be confined closely relative to said casing so as to be vaporized prior to discharge through said lower housing outlet.

10. In a vent valve for a steam system, a casing having a chamber for communication with the system and to be heated by steam admitted

from the system, said chamber having an outlet port at its upper end portion, an automatic valve in said chamber and controlling said port to allow the passage of air through said port thereby to vent the system, said valve being adapted to prevent the flow of steam through said port, a housing overlying and surrounding said casing and having an imperforate side wall and an apertured top wall, a manually operable valve means cooperable with said port and having a movable portion extending through said top wall aperture, and means for discharging adjacent the bottom wall of said housing fluid passing through said port, said steam heated casing acting to vaporize any entrained water in the vented air prior to discharge thereof through said discharging means.

11. In a vent valve, a casing having a chamber with an outlet port at its upper end portion, said casing having an inlet nipple extending from its side wall adjacent its lower end portion, an automatic valve in said chamber and controlling said port, a housing overlying and surrounding said casing and having an imperforate side wall and an aperture through its top wall, a manually operable valve means cooperable with said port and having a movable portion extending through said top wall aperture, said casing having in its side wall adjacent its lower end a slot through which said nipple extends and means for securing said housing to said casing solely at said chamber upper end portion.

12. An air vent valve comprising a casing having a port in its top wall with a downwardly directed open-ended passageway on the inlet side of and leading to said port, a float member in said casing, an upwardly extending stem on said float member, a valve on said stem operable to directly engage said casing to close said port, a valve member movable into cooperable relation with the wall of said casing on the inlet side of said port thereby to reduce flow through said port, said valve member being apertured to receive said stem so that said valve member is reciprocally guided by said stem, and a shoulder on said stem supporting said valve member in a position relative to said passageway such that air flow will lift said valve member into said cooperable relation when said valve is open thereby to reduce air flow through said port, said valve acting upon engagement with said casing to cause an equalization of pressures acting on said valve member thereby to cause said valve member to move into engagement with said shoulder and out of said cooperable relation.

13. An air vent valve comprising a casing having a port in its top wall and a downwardly extending tubular member defining a passageway leading to said port, said tubular member having a lower end wall which forms a seating portion, a float member in said casing, an upwardly extending stem on said float member, a valve on said stem operable to close said port, a thin plate-like disk member engageable with said seating portion to reduce flow through said port, said disk member being apertured to receive said stem so that said disk member is reciprocally guided by said stem, and a shoulder on said stem supporting said valve member in a position relative to said passageway such that air flow will lift said disk member into engagement with said seating

portion when said valve is open thereby to reduce air flow through said port.

14. An air vent valve comprising a casing having a vent port at its upper end, a housing having a top wall and an imperforate side wall and overlying and surrounding said casing, means securing said housing solely at its upper end to the upper end of said casing, said housing providing around said casing a downward discharging passageway leading from said port to silence the noise of air discharging from said port, and an automatic valve in said casing controlling said port.

15. An air vent valve comprising a casing having a vent at its upper end, a housing having a top wall and an imperforate side wall and overlying and surrounding said casing, said housing being supported at its upper end on the upper end of said casing and providing around said casing a downward discharging passageway leading from said port, an automatic valve in said casing engageable with the wall of said casing and controlling flow through said port, a pressure responsive valve carried by said automatic valve and controlling the inlet to said port, a manually operable valve controlling the outlet from said port, said housing having an opening in its top wall adjacent said manual valve, and means extending into said opening for adjusting said manual valve to require an increased pressure in said casing for movement of said responsive valve into position to reduce flow through said port.

16. A vent valve comprising a casing having an opening through its top wall, a valve seat member closing said opening and having a passageway therethrough, an automatic valve in said casing controlling flow through said passageway, an inlet nipple projecting from the casing side wall adjacent its lower end, and a housing having a top wall and an imperforate side wall apertured to receive said nipple, said housing being secured to and hanging from said seat member and providing around said casing a downward discharging passageway.

17. An air vent valve comprising a casing containing a chamber and having a top wall with a passageway therethrough leading from said chamber, said wall having seat portions substantially concentric with said passageway and spaced from each other, a float member in said casing, an upwardly extending stem on said float member, a valve on said stem operable to engage the innermost one of said seat portions to close said passageway, a valve member cooperable with said top wall and engageable with the outermost one of said seat portions to reduce flow through said passageway, said valve member being apertured to receive and to be reciprocally guided on said stem, and a shoulder on said stem supporting said valve member in a position relative to said passageway such that when said float member valve is open, air flow will lift said valve member toward said outermost one of said seat portions thereby to reduce air flow through said passageway, said float member valve acting upon its engagement with said innermost one of said seat portions to cause an equalization of pressures acting on said valve member so that said valve member will move away from said outermost one of said seat positions and into its supported position on said shoulder.

LEWIS W. EGGLESTON.
